(57) **CLAIM**

The ornamental design for ruggedized multichannel handheld radio with battery pack and accessory module, as shown and described.

DESCRIPTION

FIG. 1 is a front perspective view of a ruggedized multichannel handheld radio with battery pack and accessory module, showing my new design, shown the accessory module removed;

FIG. 2 is a back perspective view thereof;

FIG. 3 is a front view thereof;

FIG. 4 is a back view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a front perspective view thereof, shown with the accessory module and battery pack attached;

FIG. 10 is a back perspective view thereof;

FIG. 11 is a front view thereof;

FIG. 12 is a back view thereof;

FIG. 13 is a left side elevation view thereof;

FIG. 14 is a right side elevation view thereof;

FIG. 15 is a top plan view thereof;

FIG. 16 is a bottom plan view thereof;

FIG. 17 is a front perspective view thereof, shown with the battery pack and accessory module removed;

FIG. 18 is a back perspective view thereof;

FIG. 19 is a front view thereof;

FIG. 20 is a back view thereof;

FIG. 21 is a left side elevation view thereof;

FIG. 22 is a right side elevation view thereof;

FIG. 23 is a top plan view thereof;

FIG. 24 is a bottom plan view thereof; and,

FIG. 25 is a perspective view thereof.

In the drawings, the broken lines shown in the figures that are immediately adjacent to the shaded areas and define unshaded regions represent the bounds of the claim. All other broken lines, including the broken lines on the bottom surface of FIGS. 24-25 that show the central circular feature, are directed to the environment. The broken lines form no part of the claimed design.
